UNITED STATES PATENT OFFICE.

MATHEW ABT, OF NEW YORK, N. Y

ELECTRIC SIGNAL CONTROL.

No. 846,276.

Specification of Letters Patent.

Patented March 5, 1907.

Application filed March 26, 1906. Serial No. 308,031.

To all whom it may concern:

Be it known that I, MATHEW ABT, a citizen of the United States, and a resident of the city of New York, borough of Manhattan, in the county and State of New York, have invented a new and Improved Electric Signal Control, of which the following is a full, clear, and exact description.

My invention relates to electric signal controls, and more particularly to a system for use in connection with elevators for the purpose of enabling passengers to hail cars and for apprising passengers of the approach of said cars.

In most of the systems heretofore used each car immediately before arriving at a floor upon which a passenger has given a signal causes a lamp upon that floor to flash, for an instant only, in order to apprise the passenger of the approach of the car. By my system, however, when a passenger gives the proper signal to hail a car he causes the latter, whether descending or ascending, to light lamps and to maintain them luminous until the arrival of the car. In my system, as in other systems, a signal given by the passenger will have the effect of hailing any car traveling in the proper direction in cases where there are a number of cars otherwise independent of each other.

Reference is to be had to the accompanying drawings, forming a part of this specification, in which similar characters of reference indicate corresponding parts in all the figures.

Figure 1 is a central vertical section showing one of the automatic switchboards—say A—taken upon the line 1 1 of Fig. 2 looking in the direction of the arrow and the gear mechanism whereby this switchboard is operated by the movements of one of the elevator-sheaves. Fig. 2 is a front elevation of this same switchboard, showing the relative arrangement of the rocking sectors used for successively opening and closing the various signaling-circuits, the several movable parts being in the positions they occupy when the elevator-car is at the bottom and is just starting upward. Fig. 3 is another front elevation of the same device, but showing the movable parts in the positions they occupy when the elevator-car is at the top of the building and starting downward. Fig. 4 is an enlarged fragmentary section upon the line 4 4 of Fig. 2 looking in the direction of the arrow and showing the details of the contact mechanism in the switchboard. Fig. 5 is a cen-

tral section through one of the push-buttons used upon the different floors or landings and operated at the will of the passengers. Fig. 6 is another central section through one of these push-buttons, taken on the line 6 6 of Fig. 5; and Fig. 7 is a diagram of the wiring as used in a building containing two elevators and having in this instance two floors.

The several switchboards A B are all exactly alike, and each represents a distinct elevator-shaft having a single car. The two floors represented in the diagram Fig. 7 may be considered as the fourth and fifth floors of an eight-story building. The push-buttons C E are used by passengers upon the respective fourth and fifth floors for indicating to the operators of descending cars that the passengers upon these floors wish to descend. The push-buttons D F are used by passengers upon these same respective floors for indicating that they wish to ascend. The precise manner in which the signal is given by a passenger to the operator of the car, and vice versa, is hereinafter described in detail.

I do not limit myself to the particular arrangement of the wiring shown nor to the exact purposes elsewhere stated for the use of my system, as the same may be changed within reasonable limits without departing from the spirit of my invention.

The automatic switchboards A and B may be located either at the top or the bottom of the elevator-shafts; but in the present instance they are shown as at the top thereof. A cross-beam 10 is provided with a bearing 11, carrying a revoluble head 12, supporting a sheave 13. Over this sheave a cable 14 passes in the usual manner to the movable car. Connected with the revoluble head 12, by means of a shaft inclosed within the bearing 11, is a revoluble disk 15, provided with a radially-disposed boss 16. Mounted upon the beam 10 is a board 17, and secured rigidly to this board is a bearing-bracket 18. Supported upon this bearing-bracket is a panel 19, of insulating material, constituting the framework of one of the switchboards, such as A. Passing loosely through the center of this panel 19 is a rocking shaft 20, which is engaged by an annular bearing 21 and partially supported thereby. Rigidly mounted upon this rocking shaft 20 is a cam 22, provided with a lobe 22^a. Also mounted rigidly upon the shaft 20 is a star-wheel 23. A rocking lever 24 is journaled upon a pivot-pin 25, the latter entering a bead 26 of arcu-

ate form, (see Fig. 1,) and allowing the rocking beam 24 to move radially within certain limits upon the pin 25, as indicated in Figs. 2 and 3. This rocking lever 24 is of a general 5 arcuate form and is provided upon its ends with pressure-plates 27 28, made, preferably, of metal and insulated from the rocking lever by means of disks 29, of insulating material, as indicated more particularly in Fig. 4. 10 Sunken within each panel 19 and covered by a plate 19^a, of insulating material, are two push-buttons 30 30^a. (Shown more particularly in Fig. 4.) Each push-button is provided with a spiral spring 31 and a plunger 32, against which the spring constantly 15 presses. The plungers 32 terminate in bosses 33 34. By moving the rocking lever 24 into one or the other of its extreme positions the boss 33 or the boss 34, as the case may be, is pushed inwardly by the pressure-plate 27 or 20 the pressure-plate 28, as shown in Fig. 4. Each boss is encircled by a ring 35, of insulating material, this ring being carried by an annular disk 36 or 37 of metal. Each annular disk 36 37 is engaged directly by the 25 spring-plunger 32 immediately adjacent thereto, when the boss 33 or 34 is free to protrude through the ring 35. When one of the disks 36 37 is thus in contact with its plunger, 30 the other disk is disengaged from its plunger. By this means only one of the disks 36 37 can at a particular moment be in electrical communication with its plunger and with its particular binding-post 38 or 39, as will be understood from Fig. 4. 35

Mounted upon each panel 19 are two contact-strips 40 41, disposed concentrically and each having substantially the form of a semi-circle. Two semicircular rows of push-buttons 42^a 43^a are embedded within the panels, respectively, the push-buttons of the inner row being provided with protruding bosses 42 and those of the outer row with protruding bosses 43. These push-buttons are of 40 the construction above described, with the exception that the continuous semicircular contact-strips 40 41 are substituted for the metallic disks 36 37. Stationary contact-rods 44 45 are disposed in concentric semi-circles, as indicated in Figs. 1 and 2.

In the switchboard B wires 46 47, respectively, connect the outer and inner contact-strips 41 40 with the metallic disks 37 38. Similarly in the switchboard A a wire 48 connects the outer contact-strip 41 with the disk 37 and a wire 49 connects the inner contact-strip 40 with the disk 36. 55

A battery is shown at 50, and from this battery a wire 51 leads upwardly through the 60 several floors for which the elevator is provided. Branching off from the wire 51 at the different floors are wires 52, and connected with the latter upon each floor are wires 52^a, 53, and 54. The wires 54 53 are connected with contact members 55 56. Mat-

ing the contact member 55 is another contact member 57, and mating the contact member 56 is a contact member 59. Wires 58 60 are connected, respectively, with the contact members 57 59. 70

Each push-button C, D, E, and F is provided with a contact-bridge 61, which is adapted to engage the two contact members 55 57 or 59 56, so as to place them in electrical communication with each other. Each 75 of the push-buttons C, D, E, and F is further provided with a case 62. Mounted within this case are the several pairs of contact members 55 57 and 56 59, which are pivoted, as indicated in Figs. 5 and 6, and are pressed upon by leaf-springs 57^a. Within the cases 62 are solenoids 63 64, connected by a wire 66 with the wire 52^a by means for a junction 65. Each solenoid has a movable core 68, upon which the bridge-contact member 61 is 80 mounted. Bosses 69, 70, 71, or 72 are connected rigidly with each core 68 and protrude from the case 62, as indicated in Figs. 5 and 6. By pressing upon the boss the iron core 68 is moved relatively to the solenoid 63 and the contact-bridge 61 is brought into engagement with the contact members—say 55 57—so as to connect the two together. From the solenoid 64 of the push-button C a wire 73 leads upwardly and is connected with two 85 wires 74 75, leading, respectively, to the switchboards A B and connected with the appropriate contact-rods 44, representing the fourth floor, and hence placed fourth from the left-hand ends of the respective 90 semicircular contact-strips 40. Similarly from the solenoid 63 of the push-button D a wire 76 leads upwardly and is connected with wires 77 78, which lead to the particular contact-rods 45, representing the floor in question. From the solenoid 64 in the push-button E a wire 79 is connected with wires 80 81, which lead to the different switchboards A and B and there connect with the fifth push-button 44, representing the fifth floor. From the solenoid 63 of the push-button F a wire 82 leads upwardly and connects with the wires 83 84, which terminate in the fifth contact-rods 45 of the outer semicircle. 95 100 105 110 115

A wire 85 leads to two incandescent lamps 86 87, the lamp 86 being disposed in a hall and the lamp 87 being disposed in the elevator-shaft. The lamp 86 is for use of the passengers, whereas the lamp 87 is to attract the attention of the car operator. These two 120 lamps are in parallel with each other and connected to a wire 88, which leads to the switchboard A, terminating in the fifth push-button of the contact-strip 41, and therefore representing the fifth floor upon which the push-button F is located. 125

It will be understood that the several successive push-buttons of the contact-strips 40 and 41 represent the several successive floors in the order in which they appear to a person 130

going upward in a car. This arrangement is due to the fact that it is desirable to have a passenger press one of the upper push-buttons D F if he wishes to ascend or to press one of the lower push-buttons C E if he wishes to descend.

A wire 89 is connected with the wire 60 in the push-button E and with lamps 90 91 in parallel with each other, as above described, these lamps being connected with a wire 92, which leads to the fifth successive push-button, (reckoning from the left of the semicircle,) represented by a boss 42 upon the lower contact-strip 40 of the switchboard A. From the wire 58 (fifth floor) a wire 93 connects with incandescent lamps 94 95, the lamp 94 being disposed in the hall for the observation of passengers and the lamp 95 being in the shaft for the observation of the operator of the elevator-car. A wire 96 (fifth floor) is connected with these lamps and leads upwardly to the switchboard B and to the fifth push-button upon the contact-strip 40, representing the particular floor upon which the push-button F is located. Similarly a wire 97 is connected with lamps 98 99, the lamps being joined by a wire 100, which leads upwardly to the fifth push-button of the contact-strip 40. A wire 101 (fourth floor) is connected with lamps 102 103, the latter communicating by a wire 104 with the fourth push-button of the lower contact-strip 41. A wire 105 communicates with lamps 106 107, the lamps being connected by a wire 108 with the fourth push-button upon the lower contact-strip 40, the push-button in question of course representing the fourth floor. A wire 109 is connected with the lamps 110 111, the lamps being in communication, by means of a wire 112, with the fourth push-button of the contact-strip 41. A wire 113 is connected with lamps 114 115, and by means of a wire 116 the lamps are in communication with the fourth push-button 42 upon the contact-strip 40.

In the switchboard B the bosses 33 34 are connected by wires 118 117 with a wire 119, which taps onto the return-wire 120; which leads to the battery 50. Similar wires 121, 122 connect the bosses 33 34 with a wire 123, which also taps onto the return-wire 120. A spider 124 is mounted rigidly upon the rocking shaft 20 and is revoluble therewith. This spider is provided with a semicircular sector 125, the latter being provided on its under face with a sector 125, of insulating material, adapted to successively push the bosses 43 as the spider 124 is turned upon its axis. Another sector 126, also semicircular in form, but smaller than the sector 125, is disposed oppositely to the sector last mentioned, as indicated in Figs. 1 and 3. This sector 126 is likewise provided with a cushion or face 26^a, of insulating material, which is adapted to depress the several bosses 42 in succession as

the spider is turned in the proper direction, as will be understood from Fig. 4.

With the parts in the position indicated by Fig. 2 (the elevator being about to start upward) the spider is about to begin a half-revolution in a clockwise direction. In Fig. 3 (representing the position of the parts when the elevator is at the top and about to start down) the spider is about to turn a half-revolution in a contra-clockwise direction. When the spider turns in a clockwise direction, the several bosses 43 are pushed inward in succession, beginning at the left and ending at the right. While this is occurring the same clockwise movement of the spider causes the bosses 42 to be released one at a time, beginning at the left and ending at the right—that is to say, during the clockwise movement just mentioned the bosses 43 are released and allowed to resume their respective normal positions, and at the same time the bosses 42 are depressed in the same order, beginning with the one at the left. The several contacts controlled by the bosses 43 are therefore closed. When, therefore, the parts are in the position indicated in Fig. 2, the several contacts represented by the bosses 43 are all closed and those represented by the bosses 42 are all opened; but as soon as the spider begins to turn in the clockwise direction, representing the beginning of the ascent of the elevator from the bottom of the shaft, the several contacts represented by the bosses 43 are opened successively, the contacts represented by the bosses 42 being closed successively and in the same order. When, therefore, the elevator reaches the top and the spider completes its half-revolution, so as to occupy the position in Fig. 3, all of the contacts represented by bosses 42 are closed and all those represented by bosses 43 are opened. When the elevator is at the bottom of the shaft and the rocker 24 occupies the position shown in Fig. 2, the contact represented by the boss 34 is closed and the one represented by the boss 33 is open. When, however, the elevator reaches the top of the shaft, as indicated in Fig. 3, the rocker 24 assumes a different position and the contact represented by the boss 34 is open, while that represented by the boss 33 is closed. The purpose of this arrangement is to enable the rocker 24 to control two circuits, each provided with its parallel connections. One of these circuits is used for lighting lamps and performing other work while the elevator is ascending, the other circuit being similarly provided for use while the elevator is descending.

Mounted upon the sector 125 is a contact bridge 127, adapted to connect the sector 41 with any one of the contact-rods 45 as the contact-bridge 127 moves radially around. A similar contact-bridge 128 is mounted upon the sector 126 and is adapted to con

nect the several contact-rods 44 in succession with the sector 41. The general object of the bridge-contact members 127 128 is to complete momentary circuits for the purpose 5 of restoring the push-buttons shown in Figs. 5 and 6 and located upon the respective floors to their respective normal position for use by passengers.

My device is used as follows: Suppose that 10 a passenger is upon the fifth floor (represented by the center of the sheet, Fig. 7) and wishes to ascend. There being more than one elevator he does not know which one traveling upward will be first to arrive. He presses 15 the knob 71, this being the conventional signal. The armature 61 of this push-button is brought into engagement with contact members 55 57 and serves as a bridge therebetween. If now no elevator is ascending or 20 is at the bottom ready to ascend, the rocker 24 in any of the switchboards will be in proper position to allow a circuit to be closed through the boss 33. If, however, no elevator is ascending or about to ascend, (see Fig. 2,) the rocker 24 appertaining to that elevator 25 is in such a position as to leave the boss 34 protruding, and thus closing that part of the circuit. The passenger having pressed the button, as above indicated, looks at the lamp 30 86 to see if it lights up. If it does not light up, he knows that all of the elevators are going downward or else are at the top. As soon as, however, he sees the lamp 86 light up he knows that some one of the elevators has 35 reached the bottom of its shaft and has started upward. If, as is generally the case, some one of the elevators is already ascending at the time when he presses the push-button F, the lamp 86 will light up instantly. When 40 the lamp 86 is lighted, the lamp 87, being in parallel with it in practically the same circuit, is lighted also. The circuit is as follows: battery 50, wire 51, wire 52, wire 54, contact mechanism 55 61 57 of push-button F, wire 45 58, lamps 86 87, wire 88 to the fifth boss 43 of the semicircular sector 41, reckoning from the left end thereof to the right, this boss being uncovered and the contact represented by it being consequently closed, (see Fig. 2, also 50 detail at the left in Fig. 4,) sector 41, wire 48, contact represented by boss 34, (now closed, see Fig. 2,) wires 122 123 120 back to battery 50. This circuit energizes the lamps 86 87, as above explained. The lamps 86 87 burn 55 continuously until the elevator reaches the fifth floor. The operator, observing the light 87, stops his car and takes the passenger aboard. At the moment when this occurs the contact-bridge 127 is at the fifth boss 43, counting from the left, and depresses the boss 60 in question—that is, opens the circuit above traced and darkens the lamps 86 87, for the reason that these lamps are no longer needed. The contact-bridge 127 now engages the con-

tact-rod 45 and places the latter in electrical 65 communication with the sector 41, and thus completes a momentary circuit as follows: battery 50, wire 51, wire 52, wires 52^a 66, solenoid 63, wire 82, wire 83 to fifth contact-rod 45, reckoning from the left of the switchboard A, contact-bridge 127, sector 41, wire 48, contact represented by boss 34, wire 122, wire 123, wire 120, back to battery 50. The circuit just traced momentarily energizes the solenoid 63, and the latter acting mechanically upon its iron core withdraws contact-bridge 61 from the contact members 55 57, and thus restores the knob 71 to its normal 70 position. However, the circuit through lamps 86 87 is now broken and must remain 75 broken until the knob 71 is pressed again. If a passenger is at the fourth floor and wishes to ascend, he presses the knob 69, lighting the lamps 102 103. When he is taken aboard the car, the push-button is automatically restored to its normal position and the lamps 102 103 are extinguished. In other words, the action of the push-button D and of circuits relating thereto is quite 80 analogous with the same effects stated in connection with the push-button F.

If at the time when the passenger presses the button F, as above described, the elevator represented by the switchboard A is not ascending, but the one represented by the 95 switchboard B is ascending or ready to ascend, the lighting-circuit will be complete as follows: battery 50, wire 51, wire 52, wire 54, contact members 55 61 57 of push-button F, wire 58, wire 93, lamps 94 95, wire 96 to 100 fifth boss 43 of switchboard B, sector 41, wire 46, wire 117, wire 119, wire 120 back to battery 50. This will light the lamps 94 95 instead of the lamps 86 87 and will apprise the passenger that the elevator he should 105 take is the one indicated by the lamps. Similarly when he boards the car the lamps 94 95 are darkened and the push-button F is restored to its normal condition. Similarly 110 if there be other elevators they have their respective lamps, which are lighted and darkened as above described by circuits analogous to those already traced.

Suppose now that a passenger is on the 115 fifth floor and wishes to descend. He presses the knob 72 of push-button E, thereby completing the following circuit: battery 50, wire 51, wire 52, wire 53, contact members 56 61 59, wire 60, wire 89, lamps 90 91, wire 92 to switchboard A, fifth-boss 42, sector 120 40, wire 49, boss 33, (and contact associated therewith,) wires 121 123, wire 120, back to battery 50. This causes the circuit to be completed through the lamps 90 91; provided 125 the rocker 24 (see Fig. 3) is in such position that the contact represented by the boss 33 is closed; but not otherwise. In other words, a passenger pressing knob 72 of push-button

It is enabled to light the lamps 90 91 if the elevator pertaining to the switchboard A is either descending at some point above the fifth floor or is at the top and ready to descend. If, however, some other elevator, such as represented by switchboard B, is about to descend or is descending and is above the fifth floor, the lamps 98 99 are lighted through the circuit analogous to that through the lamps 90 91. Each elevator, therefore, to some extent controls its own lamps, which are independent of the lamps controlled by other elevators. If the passenger is on the fourth floor and wishes to descend, he presses the button C, thus lighting the lamps 106 107 in case the elevator represented by switchboard A is descending or about to descend or lighting the lamps 114 115 in case the other elevator is descending or about to descend. The elevator arriving at the floor in question the passenger is taken aboard, and the circuit through the lamps is broken in the manner above described—to wit, the contact-bridge 128 (see Figs. 2 and 3) by connecting the contact-rod 44 with the sector 40 completes a momentary circuit through the solenoid 64 and causes it to withdraw the bridge 61, and thus break the lamp-circuit.

From the above description it will be seen that a passenger wishing to ascend can hail any descending car which has not yet reached the platform upon which he stands and that in so doing the approach of the car not only lights two lamps, but keeps them burning continuously until the car arrives, no matter how much time this may require.

The system is economical of power, for the reason that if a passenger presses in a knob of a push-button no current flows through any of the lamps in consequence until some one of the elevators is upon the route which the passenger desires to travel.

While I show push-button contacts, it will be understood that contacts of many other kinds are old and well known in this art and that I may substitute such other contacts instead of the push-button contacts. It will be also understood that I do not limit myself to the exact construction shown, as the details of my invention may be varied within

wide limits without departing from the spirit of the invention.

Having thus described my invention, I claim as new and desire to secure by Letters Patent—

1. The combination of a plurality of contacts normally closed, electric lamps mounted upon different floors and connected with said contacts respectively, mechanism controllable by movements of a revoluble member for opening said contacts successively, so as to darken said lamps in a predetermined relative order corresponding to that of the successive floors, and mechanism for opening a plurality of lamp-circuits while said elevator is traveling in a particular direction.

2. The combination of a revoluble member connected with the hoisting mechanism of an elevator, said revoluble member being provided with a boss, a star-wheel to be turned step by step as said revoluble member is turned, a cam connected with said star-wheel, a rocker disposed partially within the path of said cam so that said rocker is actuated by movements of said cam, contacts to be opened and closed by movements of said rocker, one of said contacts being opened whenever the other is closed, and separate circuits each connected with one of said contacts and controllable thereby for signaling the arrival of the elevator from a particular direction only.

3. In an electrical signal system, the combination of a plurality of contacts normally closed and representing different floors, mechanism controllable by movements of an elevator for opening said contacts in a predetermined successive order representing the succession of different floors to be passed by the elevator-car, electric lamps connected with said contacts and lighted thereby, and means controllable by movements of the car through predetermined distances for opening a plurality of circuits through said lamps.

In testimony whereof I have signed my name to this specification in the presence of two subscribing witnesses.

MATTHEW ABT.
